(57) CLAIM

The ornamental design for a combined snowmobile headlight with cowling, as shown and described.

DESCRIPTION

FIG. 1 is a front view of the combined snowmobile headlight with cowling, showing our new design;

FIG. 2 is a rear view of the combined snowmobile headlight with cowling;

FIG. 3 is an enlarged left side-elevational view of the combined snowmobile headlight with cowling;

FIG. 4 is an enlarged right side-elevational view of the combined snowmobile headlight with cowling;

FIG. 5 is a top view of the combined snowmobile headlight with cowling; and,

FIG. 6 is a bottom view of the combined snowmobile headlight with cowling.

The broken lines are included for the purpose of illustrating portions of the combined snowmobile headlight with cowling that form no part of the claimed design.

1 Claim, 6 Drawing Sheets
